UNITED STATES PATENT OFFICE.

ROBERT WILSON, OF HAMILTON, ONTARIO, CANADA, ASSIGNOR TO OTIS-FENSON
ELEVATOR COMPANY, LIMITED, OF TORONTO, CANADA.

AUTOMATIC ELEVATOR-GATE LOCK.

1,159,457.

Specification of Letters Patent.

Patented Nov. 9, 1915.

Application filed April 22, 1915. Serial No. 23,068.

To all whom it may concern:

Be it known that I, ROBERT WILSON, of the city of Hamilton, in the county of Wentworth, in the Province of Ontario, Canada, have invented certain new and useful Improvements in Automatic Elevator-Gate Locks, of which the following is the specification.

My invention relates to improvements in automatic elevator gate locks and the object of the invention is to devise a lock which will insure of the gate being held in its raised position without danger of being accidentally released by lateral movement of the elevator platform and it consists essentially of a cam shoe carried by the elevator platform, a spring held latch carried by the side guide post of the elevator gate, a cam lever also carried by the post and spring held outwardly in the path of the cam shoe, a projecting finger extending from such lever against the latch whereby the latch is carried into the path of the gate counterweight when the cam lever is engaged by the cam shoe, such counterweight having an upwardly presented portion extending beneath the latch when in the engaged position as hereinafter more particularly explained by the following specification.

Figure 1, is a view in elevation of the side guide posts and elevator gate held therebetween and broken away intermediate of its length, the posts being partially broken away and in section to exhibit a portion of the interior mechanism. Fig. 2, is a vertical section through Fig. 1 taken through the gate and through the locking mechanism showing a portion of the platform and the cam shoe carried thereby out of engagement with the locking mechanism. Fig. 3, is a similar view to Fig. 2 showing the cam shoe in engagement with the locking mechanism. Fig. 4, is a similar view to Figs. 2 and 3 showing the cam shoe in engagement with the locking mechanism and the elevator gate in the raised position. Fig. 5, is an enlarged sectional detail of the locking mechanism. Fig. 6, is a front elevation of the locking mechanism as shown in Fig. 5. Fig. 7, is a perspective detail of one of the pulley blocks for supporting the gate.

In the drawings like letters of reference indicate corresponding parts in each figure.

1 and 2 indicate the side guide posts of the elevator gate.

3 indicates the elevator gate slidably carried on angle bars indicated by the numeral 4.

5 indicates a portion of the elevator platform.

5^x indicates the floor level and 6^x the ceiling level.

6 indicates a cam shoe secured to the platform 5, such shoe being provided with a vertical face indicated by the numeral 7 65 located adjacent to the side guide post 2. The side guide posts 1 and 2 are hollow so as to form vertical ways.

8 indicate the counterweights of the elevator gate 3.

9 indicate cords connected at one end to the weights 8 and at the opposite end to the elevator gate 3.

10 indicate brackets in which the pulleys indicated by the numeral 11 are journaled. 75 The brackets 10 are provided with a flat horizontally extending portion indicated by the numeral 12.

13 indicates a slot formed in the horizontal portion 12. The cords 9 pass over 80 the pulleys 11 being supported thereby.

14 indicates a slot formed in the side guide post 2.

15 indicates a casting secured to the face of the post 2 and provided in proximity to 85 its upper end with lugs 16 (see Figs. 5 and 6) and in proximity to its lower end with lugs 17.

18 and 19 indicate pins extending through and secured within the lugs 16 and 17.

20 indicates a cam lever swung in proximity to its upper end upon the pin 18.

21 indicates a recess formed in the casting 15 and 22 indicates a teat extending from the cam lever 20.

23 indicates a spiral spring fitting within the recess 21 at one end and extending around the teat at the opposite end so as to hold the cam lever 20 in a normal outward position.

24 indicates a lever extension extending upwardly therefrom above the pin 18. The

extension 24 bears against the face of the casting 15 when the cam lever 20 is in its outermost position thereby limiting the outward movement of the lever. The outer 5 face indicated by 25 of the lever 20 is suitably curved so as to form a cam surface.

26 indicates a projecting finger which extends inwardly from the lever 25.

27 indicates a latch piece swung upon a 10 pin 19.

28 indicates a spring which is wound around the hub of the latch piece 27, one end indicated by 29 extending upwardly and bearing against a suitable portion of the 15 casting 15 and the opposite end indicated by 30 extending upwardly and bearing against the under face of the latch piece 27.

31 indicates tooth projections extending from the counter weight 8.

20 32 indicates a block through which the cord 9 extends, the block being secured in position on the cord by a knot indicated by the numeral 33 formed in the cord beneath the weight.

25 34 indicates a spiral spring surrounding the cord 9 above the weight 32 and carried by the weight.

Having described the principal parts involved in my invention I will briefly describe the operation of the same.

When the elevator platform is traveling downwardly in the direction of arrow (see Fig. 2) the portion 7 of the cam shoe engages the cam lever 20 swinging it inwardly 35 into the position shown in Fig. 3, against the outward pressure of the compression spring 28 and thereby forcing the latch piece 27 into a horizontal position by means of the inwardly projecting finger 26. If the 40 elevator platform stops at the floor level indicated by the numeral 5 the latch piece is held in a horizontal position. The elevator gate 3 is then raised thereby allowing the counter weight 8 to drop, the teeth of the 45 counterweight passing the latch piece 27, such latch piece being swung downwardly from a horizontal position against the tension of the spring 28. As soon as the tooth projection 31 is passed the latch piece flies 50 up again into engagement with the finger 26 holding the latch piece in the horizontal position above the tooth 31. In the drawing two teeth 31 are shown in order that if one tooth should miss the other one would engage.

55 It has been found that in all automatic locks the great detriment has been that they are very easily freed by a very slight lateral movement of the elevator platform carrying 60 the cam shoe 6 away from the side guide post and causing the sudden dropping of the elevator gate which is often the cause of accident to persons who may be passing beneath the gate at the time. In my construc-

tion the locking mechanism is so formed 55 that it will not free even though the elevator platform moves laterally to its maximum extent and the gate cannot become freed until the elevator platform is either moved above or below the floor level. The 70 gate is then automatically freed by the cam lever flying outward and the latch upward so as to free the counterweight 8.

In order to cushion the gate as it drops to the closed position I have provided the 75 spring 34 hereinbefore described which engages at its upper end with the bottom face of the horizontal extension 12 of the bracket 10 when the gate comes to its closed position and therefore breaks the fall of the gate. 80

From this description it will be seen that I have devised a very simple form of locking mechanism which will lock a gate in a positively open position when the gate is raised and the platform is at the floor level 85 and which cannot be released until the platform leaves such floor level.

What I claim as my invention is:

1. The combination with a cam shoe carried by an elevator platform and elevator gate counterweight having an upwardly presented engaging face, of a suitably supported spring held latch designed to be swung inwardly above the engaging face of the counterweight, a spring pressed cam lever 95 swung upon a suitable support and projecting into the path of the cam shoe, and a finger extending inwardly from the cam lever against the latch.

2. The combination with a cam shoe carried by an elevator platform and elevator gate counterweight having tooth like projections, of a suitably supported spring held latch designed to be swung inwardly into the path of the tooth like projections, a 105 spring pressed cam lever swung upon a suitable support and projecting into the path of the cam shoe, and a finger extending inwardly from the cam lever against the latch.

3. In an elevator gate locking mechanism, 110 the combination with a cam shoe carried by the elevator platform and elevator gate counterweight provided with an upwardly presented engaging face, of a suitably supported latch, a spring pressed cam lever, and 115 means operated by the engagement of the cam shoe with the cam lever for carrying the latch into the path of the engaging face of the counter weight.

4. In a device of the class described, a 120 latch piece swung upon a suitable support, and a cam lever also swung upon the support and provided with a finger projecting forwardly against the latch piece whereby the latch piece is forced into a horizontal 125 position when the cam lever is swung down.

5. In an automatic elevator gate lock, the combination with the gate counterweight

having an upwardly presented engaging face, of a suitably supported spring held latch, a suitably swung lever provided with a finger bearing against the aforesaid latch,

Witnesses:

ROBERT WILSON.

5 and means operated by the descent of the elevator for forcing the lever inwardly
